Des. 222,179
Patented Oct. 5, 1971

222,179

FISH SKINNER

Donald L. Beasley, Des Moines, Iowa, assignor to
Townsend Engineering Company, Des Moines, Iowa

Filed June 17, 1970, Ser. No. 23,536

Term of patent 14 years

Int. Cl. D7—99

U.S. Cl. D44—29

Fig. 1.

Fig. 2.

Fig. 3.

Fig. 4.

FIG. 1 is a perspective view of a fish Skinner showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a right side elevational view thereof; and

FIG. 7 is a bottom plan view thereof.

I claim:

The ornamental design for a fish Skinner, substantially as shown.
